UNITED STATES PATENT OFFICE.

HARRY BAYLOR CLOUD, OF TULSA, OKLAHOMA.

MEASURING MACHINE.

Application filed February 20, 1925. Serial No. 10,629.

This invention relates to a device especially designed for measuring cloth or the like material and aims to provide novel means to facilitate the measuring and handling of cloth from the bolt.

Another important object of the invention is to provide means whereby the number of yards of cloth measured by the machine will be accurately registered, thereby enabling the proprietor of a store to keep accurate account of the number of yards of goods sold.

A still further object of the invention is the provision of means for cutting the cloth at a point where the measured cloth is to be severed from the bolt.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a measuring device constructed in accordance with the invention and illustrating the manner of supporting the same.

Figure 2 is a perspective view of the device.

Figure 3 is a longitudinal sectional view through the device.

Figure 4 is a sectional view taken on line 4-4 of Figure 3.

Figure 5 is a sectional view taken on line 5-5 of Figure 3.

Figure 6 is a sectional view taken on line 6-6 of Figure 4.

Figure 7 is an elevational view of the cutting device.

Referring to the drawings in detail, the device includes a body portion indicated generally by the reference character 5 which is formed with a central horizontally disposed cut out portion 6 through which cloth to be measured passes.

Mounted in one wall of the cut out portion 6, is a roller 7 that cooperates with the roller 8 for engaging the cloth material passing through the body portion to remove folds in the cloth and assist in holding the cloth tightly while it is being measured.

The roller 8 is formed with a shaft 9 that extends through the elongated openings 10 of the tubular member 11, which shaft operates in the bearing member 12 that is normally held downwardly by means of the coiled spring 13 that is tensioned by means of the screw 14.

Positioned under the bearing member 12 is an eccentric 15 carried at the inner end 65 of the shaft 16 that has its outer end formed into a finger piece 17 whereby the eccentric may be readily operated to raise or lower the bearing member 12 to disengage the rollers 7 and 8.

Extending laterally from the body portion is a measuring arm indicated at 18 which is formed with a bore 19 extending throughout the length thereof, the bore having one of its walls cut away providing a 75 slot 20.

The reference character 21 indicates the cloth engaging member and as shown is formed with a tubular member 22 that moves over the flexible member 23 positioned in the bore 19, the outer end of the member 23 being secured to the hook member 24 carried by the cap 25.

Positioned on the flexible member 23 is a collar 26 adapted to be engaged by one end of the tubular member 22 to move the flexible member 23 when the cloth engaging member 21 has reached the limit of its outward movement. The inner end of the flexible member 23 is connected with the arm 27 carried at the lower end of the rod 28 that extends upwardly and engages suitable gearing of the indicating members carried within the casing 29, which indicating members include hands 30 that are clearly visible from the upper surface of the body portion.

Pivotedly carried by the member 21 is an arm 31 that has a cutting blade 32 that cooperates with the blade 33, the arm being provided with a finger piece 34 which may be engaged by the thumb of the operator to move the blade 32 into engagement with the blade 33, cutting the cloth supported therebetween.

The support for the device includes arms 35 and 36 respectively, which arms have pivotal connection with the counter or table as at 37 while the upper ends of the arms are pivotally connected with the arm 18 at 38.

Pivotedly connected with the arm 18 is an arm 39 formed with cut out portions to per-

mit the arm 39 to be positioned over the pivot pin 37 so that the device may be held in various positions of adjustment.

The upper surface of the arm 8 is provided with graduations indicating a yard so that each time the member 21 is moved throughout the length of the arm 18, a yard is measured.

In the use of the device, the member 17 is operated to move the roller 8 out of engagement with the roller 7, the cloth to be measured being positioned between the rollers and the member 17 moved to allow the rollers to clamp the cloth therebetween.

The free end of the cloth is now gripped between the thumb of the operator and the finger piece of the member 21, whereupon the member 21 is slid to the outer end of the arm 18 with the result that the tubular member 22 contacts with the collar 26 moving the flexible member 23. It follows that as the member 23 is moved the rod 28 is moved to cause a movement of the registering hands 30.

When the member 21 has moved as described, it is obvious that one yard of cloth has been measured, and should it be desired to measure two yards of cloth, it is obvious that the member 21 would be returned to its

initial position and the operation above described repeated.

After the cloth has been measured, the cloth is positioned under the blade 32 and the blade 32 moved through the cloth, cut-

ting the cloth at the place where the measured section should be torn from the bolt.

I claim:—

1. A measuring device including a body portion having an opening, a registering device mounted in said opening, a measuring arm secured at one end to the body portion, said arm having a central bore and slot formed throughout its length, a flexible member in the bore and having means whereby the flexible member is connected at its inner end with the registering device, a collar secured adjacent to the outer end of the flexible member, and means movable over the flexible member and adapted to be moved with cloth being measured to engage the collar and operate the flexible member and registering device.

2. A measuring device including a body portion having an opening, said body portion having a cut out portion, a measuring arm extending laterally from the body portion, a supporting wire extending through the arm, a registering device mounted in said opening, means for connecting the wire to the registering device, and a cloth engaging member mounted on the wire and adapted to move longitudinally of the arm for operating the wire to move the registering device.

In testimony that I claim the foregoing as my own, I have hereto affixed my signature.

HARRY BAYLOR CLOUD.
